(57) **CLAIM**

The ornamental design for an air conditioning duct cover with monitor for construction machine, as shown and described.

DESCRIPTION

This application contains subject matter related to the following co-pending U.S. design patent applications:

Application Ser. No. 29/648,589, filed herewith and entitled “Seat for Operator Cab for Construction Machine”; Application Ser. No. 29/648,594, filed herewith and entitled “Console Box for Construction Machine”; and Application Ser. No. 29/648,596, filed herewith and entitled “Console Box for Construction Machine”.

FIG. 1 is a front, top and right side perspective view of an air conditioning duct cover with monitor for construction machine according to the design;

FIG. 2 is a front, top and left side perspective view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear elevational view thereof.

1 Claim, 6 Drawing Sheets
